United States Patent Office.

HANS HEINRICH ANDRESEN AND HANS ASBAHR, OF DAVENPORT, IOWA.

Letters Patent No. 78,040, dated May 19, 1868.

IMPROVED VENETIAN BLINDS.

The Schedule referred to in these Letters Patent and making part of the same.

TO ALL WHOM IT MAY CONCERN:

Be it known that we, HANS HEINRICH ANDRESEN and HANS ASBAHR, of Davenport, in the county of Scott, and State of Iowa, have invented certain new and useful Improvements in Venetian Blinds; and we do hereby declare that the following is a full, clear, and exact description thereof, reference being had to the accompanying drawings, making a part of this specification, in which—

Figure 1 is a front or inside view of the improved Venetian blind.

Figure 2 is a back or outside view of the same.

Figure 3 is an end view, showing the slats of the upper half of the blind open, and the slats of the lower half closed.

Figure 4 is an end view, showing the lower slats open and the upper slats closed.

Figures 5 and 6 are end views, showing how one-half of the slats may be elevated.

Figure 7 is an end view, showing the slats all drawn up to their highest point.

Similar letters of reference indicate corresponding parts in the several figures.

This invention relates to an improved mode of hanging and operating the slats of that class of shades for windows and doors which are denominated Venetian blinds.

Heretofore, this class of blinds have been made by attaching the narrow slats of which they are chiefly composed to narrow strips of cloth, and suspending the slats thus connected together from rollers or pulleys, by means of cords which are passed through and around the slats. Blinds thus constructed frequently get out of order by the wearing and breaking of the suspension-strips and pull-cords, and when in such condition they are not easily repaired.

The object of our invention is to improve Venetian blinds by hinging the upper or outer edges of all the slats to suspension-chains, and applying lifting-chains or other suitable connections to the front or inner edges of the slats, so that when the slats are hung up by their suspension-chains, they can be opened or closed more or less, by raising their front or inner edges by means of pull-cords, arranged as will be hereinafter described.

Another object of our invention is to construct a sectional Venetian blind, having its slats hinged to suspension-chains, in such manner that the slats of either one of the sections can be opened or closed more or less, independently of the slats of the other section, at the same time providing for opening or closing all of the slats composing the blind at one and the same time, as will be hereinafter explained.

To enable others skilled in the art to understand our invention, we will describe its construction and operation.

In referring to the construction of our improved blind, the surface which is next the window when the blind is hung up in proper position will be termed the outer surface. The slats *a a* may be made in the usual manner of making slats for Venetian blinds, with the exception that there are no holes made through the slats, of our improved blind for pull-cords. To the outer edge of each slat *a*, and at proper distances from its extremities, wire staples *b* are fastened, by means of which the slats are hinged to two suspension-chains *C C*, so as to overlap, as shown in the drawings, and to lie in planes parallel to each other.

The suspension-chains may be attached to a head-piece, *A*, or to a suitable ornamental box in any desirable manner, so that the blind can be hung up to a window. It will be seen that when the slats are thus attached to suspension-chains *C C*, by loose joints, and left free to hang, the slats will be brought together so as to make a close shade by the overlapping of their edges. It will also be seen that each slat is free to swing by its jointed connections *b*, independently of the others.

To effect the opening and closing of the slats *a*, we attach to their front edges two chains *D D'*, by means of staples *b'*; which chains are arranged in the middle of the length of the slats, and have two cords *c c'*, attached respectively to their upper ends, as clearly shown in figs. 1, 3, and 4. These cords *c c'* are carried up and passed through pulleys *d d*, upon the inner side and in the middle of the length of the head-piece *A*, and their ends are allowed to hang down freely upon the inner side of the blind. In figs. 2, 3, and 4 of the drawing, the free ends of the cords *c c'* are represented as being carried forward, so as to hang down upon the outer side of the blind, but in practice these two cords are carried down upon the inner side of the blind, or that side which is

seen in fig. 1, so that they can be readily taken hold of. If desirable, the free ends of these cords $c c'$ may be attached together, or these ends may hang independently of each other. By drawing down both of the cords $c c'$, the inner edges of the slats may be raised, so as to expose more or less light through the blind. By drawing upon the cord c , the slats composing the upper half of the blind may be opened more or less, as shown in fig. 3, and by drawing upon the cord c' , the slats composing the lower half or section of the blind may be opened more or less, as shown in fig. 4.

If desirable the blind may be divided into more than two independently movable slat-sections, by attaching the slats together by means of chains, and using separate pull-cords for each section so connected.

For the purpose of raising the slats a bodily, cord g is used, which is attached to the lowermost slat of the

blind, in the middle of the length thereof, and carried upward on both sides of the blind, and passed over

pulleys $e h$ on head-piece A ; its ends are thence carried down and tied together beneath the blind. By drawing

down upon this cord, the blind-slats may all be raised bodily, as shown in fig. 7, or, if desired, the lower half of

the blind may be raised, as shown in figs. 4 and 5.

We do not confine ourselves to the use of chains for suspending the blind-slats, and connecting the front edges of these slats together, as any other means may be employed which may be found to answer as good a purpose.

Having described our invention, what we claim as new, and desire to secure by Letters Patent, is—

1. Hinging the slats a by their edges to the suspension-chains $C G$, in combination with a lifting-chain or

chains and pull-cords, arranged substantially as described.

2. In combination with slats which are hinged and hung, substantially as described, we claim attaching the

free edges of the slats together by means of separate lifting-chains $D D'$, substantially as and for the purposes

described.

3. A Venetian blind, which is constructed and operates substantially as described.

HANS HEINRICH ANDRESEN.

HANS ASBAHR.
